CHAIR FOR CHILDREN

Reeva Kurtzman, Golden, Colo.

Application June 9, 1947, Serial No. 139,534

Term of patent 7 years

(Cl. D15—1)

To all whom it may concern:

Be it known that I, Reeva Kurtzman, a citizen of the United States, residing at Golden, county of Jefferson, and State of Colorado, have invented a new, original, and ornamental Design for a Chair for Children, of which the following is a specification, reference being had to the accompanying drawing, forming part thereof.

Fig. 1 is a front elevation of a chair for children, embodying a novel design;

Fig. 2 is a side elevation of the chair shown in Fig. 1; and

Fig. 3 is a perspective view of the chair shown in Fig. 1.

I claim:

The ornamental design for a chair for children, as shown.

REEVA KURTZMAN.
